DIRECTIONAL CHANNEL SEPARATION FILTERS

Pierre G. Marié, 16 Rue de Varize, Paris, France

Filed June 26, 1956, Ser. No. 593,886

Claims priority, application France June 30, 1955

3 Claims. (Cl. 333—10)

The present invention relates to directional channel-separation filters.

Resonant directional couplers have been constructed by the inventor which consist of two identical rectangular guides and of a circular cavity resonator which connects them together, such that a traveling wave of electromagnetic energy in the TE_{10} mode, which is propagated in a given direction in one of the rectangular guides and arrives in the junction region between the said rectangular guide and the cavity resonator, has its energy split into two parts. The first part (that which has frequencies outside the bandwidth of the cavity resonator) continues to progress in the rectangular guide to beyond the junction with the cavity resonator. The second part (that which has frequencies within the bandwidth of the cavity resonator) of this energy is radiated in the circular resonator through the intermediary of a particular first coupling in the form of a circularly polarized wave which is constituted by two waves of the TE_{11} mode which are polarized perpendicularly and in quadrature. The same circularly polarized wave radiates energy in the second rectangular guide through the intermediary of a second coupling which is similar to the first coupling and is propagated in the TE_{10} mode in a definite direction which depends upon the direction of propagation in the first rectangular guide.

In these couplers, the system of coupling between each rectangular guide and the circular cavity resonator or guide is constituted by crossing slots, the center of which is situated on the axis of the circular guide but is eccentric with respect to the axis of the rectangular guide by a quantity

$$\left(\frac{a}{2} - x_0\right)$$

such that

$$\tan \frac{\pi}{a} x_0 = \frac{\lambda_s}{2a} \quad (1)$$

wherein a is the dimension of the large side of the guide and λ_s is the wavelength in the rectangular guide.

It follows from this that these first kind directional couplers are composed of first and second rectangular guide stubs identical with each other which are connected together by a circular cavity resonator, the axis of which is eccentric with respect to the plane of symmetry passing through the axes of the two rectangular guides. This eccentric structure may have disadvantages, especially from the point of view of construction. Since the two bases of the circular cavity resonator are not entirely contained in the large faces of the rectangular guides, it is especially necessary to arrange asymmetric bottoms on the parts of these bases which are outside the said large faces.

Applicant attempts to construct directional channel-separation filters by cascade-connecting a plurality of resonant directional couplers of the above-mentioned first

2

kind in such a way that the first rectangular guide stubs of all the couplers constitute a common rectangular main guide and by giving to the circular cavity resonators of the couplers resonance frequencies in the TE_{11} mode respectively equal to the median frequencies of the channels to be separated.

The directional channel separation filters thus constructed exhibit relatively poor voltage standing wave ratios of at least 1.20 which is a serious drawback for 10 constructing directional multiplexing filters for the separation of a large number of frequency channels. This is due to the fact that the crossing slots being at a common location cannot be matched independently from each other to equalize their power coupling factors relatively 15 to the transverse and longitudinal components of the magnetic field in the rectangular waveguide. And the same impossibility is met when the off-center aperture is a single circular one.

Furthermore, these directional channel-separation 20 filters cannot be designed with standard size rectangular wave guides without the provision of flattening transitions in said wave guides at the location of couplings with the circular cavity resonators.

The object of the present invention is to construct a 25 directional channel separation filter comprising a common rectangular main wave guide, a plurality of circular cavity resonators tuned onto different resonant frequencies and an equal plurality of frequency channel rectangular wave guide stubs, having a wide number of frequency channels 30 lying in a wide bandwidth and exhibiting through the over-all bandwidth a voltage standing wave ratio quite lower than in the first kind directional channel-separation filters, say lower than 1.05.

Another object of the invention is to construct a directional channel-separation filter of the kind concerned in which the condition of complete rejection between the two arms of the main guide on one side and the other of each cavity resonator and the two arms of the frequency channel guide coupled to said cavity resonator is compatible with standard size rectangular waveguide construction.

According to the invention, the systems of slots between the circular cavity resonator and each rectangular guide of the directional coupler, the axes of which meet 45 each other or are very near each other, comprise a slot which is longitudinal with respect to the rectangular guide and located on one side of the axis of the said guide and a transverse slot, which is located on the other side of the axis, the distances between this axis and the centers 50 of the slots being fixed by relationships which will be set forth hereinafter.

Furthermore a small metallic plate is inserted in each of the rectangular guides, parallel to the wide side of the guide, and facing the portion of wall comprised between 55 the longitudinal slot and the edge of said wide side.

The invention will be better understood on reading the detailed description which will now be given and on examining the accompanying drawings, of which

Fig. 1 represents a directional coupler of the prior art; 60 Fig. 2 represents a directional coupler used in the invention;

Fig. 3 is a diagram of the junction between a rectangular guide of the coupler and the circular cavity resonator explaining the fixing of the geometrical position of the slots;

Fig. 4 is a directional channel-separation filter using a 65 plurality of couplers of the type shown in Fig. 2; and

Figs. 5a and 5b are diagrams of waveforms useful for explaining the operation of the coupler.

In Fig. 1, which represents a directional coupler of the prior art, 1 is the first rectangular guide, 2 is the second rectangular guide, 3 is the circular guide, 4 and 5 are the

systems of slots, **5** and **7** are the mouths of the guide **1**, and **6** and **8** are the mouths of the guide **2**. The centers of the slots **3** and **4** are at a distance x_0 from the edge of the rectangular guides given by the above Equation 1 and are on the axis **10** of the circular guide.

The dimensions of the rectangular guides are a and b ($a > b$) and the diameter of the circular guide is D . It is seen in Fig. 1 that the axis **10** does not meet the axes **11** and **12** of the large sides of the rectangular guides which are facing one another and that the parts **13** and **14** of the bases of the circular guide extend beyond the edge of the large faces of the rectangular guides. Naturally, these parts **13** and **14** should be closed by metallic bottoms.

Further, as will be seen hereinafter, the condition of complete rejection between the arms of the common rectangular main waveguide on one side and the other of a cavity resonator pertaining to a given channel in the frequency bandwidth of said channel occurs for ratios between the small and large side widths of said waveguide which are not those of standard size waveguides. The same is true for the complete rejection condition between the two arms of a channel rectangular waveguide.

Referring to Fig. 2, which represents a coupler used in the invention, the said coupler comprises two rectangular guides **15** and **16** and a circular guide **18**, the axis **19** of which meets the axes **20** and **21** of the large sides of the rectangular guides. The systems of slots each comprise two slots **22** and **23**, one being longitudinal and the other transverse with respect to the rectangular guides and situated respectively on one side and the other of the axes **20** and **21** of the large sides of these guides. As shown in Fig. 2, slots **23** must be integrally on one side only of the longitudinal axes **20**, **21** of the corresponding rectangular guides and must not cross the same.

Small metallic plates **24**, the very important function of which will be explained hereinafter, are arranged in the rectangular guides parallel to the large side and facing the portion of wall comprised between the edge of the large side and the longitudinal slots **22**.

In Fig. 3, the system of slots **22**—**23** is represented with reference to the axis **Oy** parallel to the axis **20** of the guide **15** and to the axis **Ox** which is perpendicular to the foregoing axis. The point **0** is the projection of the axis **19**.

If the abscissa of the side **25** of the rectangular guide **15** is denoted by $-x_0$, the abscissa of the side **26** of the same guide is denoted by $a - x_0$, the distance of **0** to the center of the slot **22** is denoted by x_1 and the distance of **0** to the center of the slot **23** is denoted by x_2 , it may be shown that, among the six quantities x_0 , x_1 , x_2 , a , b and D , there are three relationships and that one is, consequently, allowed to impose three arbitrary conditions.

These relationships may be developed by the following method: Let $-2 \cot u$ be the relative susceptance of the slots, i.e. the ratio of the susceptances of the slots respectively in the rectangular guide and in the circular guide by the admittances of said guides (see Marcuvitz, Waveguide Handbook, Radiation laboratory Series, vol. 10, page 365, McGraw-Hill Book Company, Inc., New York, 1951). It is known that $\tan u$ is proportional, at a given frequency, to the square of the component of the magnetic field along the slot of a unit power wave. Let us denote by H_{TR} , H_{LR} , H_{TC} respectively the maximum transverse magnetic field in the rectangular guide, the maximum longitudinal magnetic field in the rectangular guide and the maximum transverse magnetic field in the circular guide for a unit power wave (TE_{10} in the rectangular guide and TE_{11} in the circular guide).

The magnetic field along the slot **22** is:

$$jH_{LR} \cos \pi \frac{(x_1 + x_0)}{a}$$

in the rectangular guide and, in the circular guide:

$$jH_{TC} 2J_1'(2x_1/D)$$

where J_1' is the derivative of the Bessel function J_1 of unit order.

The magnetic field along the slot **23** is:

$$5 \quad H_{TR} \sin \pi \frac{(x_2 + x_0)}{a}$$

in the rectangular guide and, in the circular guide:

$$10 \quad H_{TC} \frac{2J_1(2x_2/D)}{x_2/D}$$

15 The traveling wave in one of the slot coupling systems, say the coupling system between guides **15** and **18** may be considered as the superposition of a double set of standing waves, applied to the two mouths of guide **15** and to the mouth of guide **18** assumed to be disconnected from guide **16** and to have its top open, and respectively symmetrical and antisymmetrical with respect to the plane x_0z . The symmetrical waves are shown in Fig. 5a and the antisymmetrical waves in Fig. 5b. As for the symmetrical standing wave in guide **18**, it is polarized in the x_0z -plane, whereas the antisymmetrical wave in the same guide is polarized in the y_0z plane. As the slots have a susceptance angle u , the nodes of the standing waves are displaced by an angular distance u from the location they would have if the slots were omitted. Now, let us associate the standing wave pattern A of Fig. 5a and the standing wave pattern B of Fig. 5b and form the pattern $A + jB$ (by superposing the pattern A with the pattern B in phase quadrature with the first); there is obtained a traveling wave in the rectangular guide and a circularly-polarized standing wave in the circular guide.

20 As already stated, $\tan u$ is proportional to the square of the component of the magnetic field along the slot. Then, by equaling the four expressions of $\tan u$, we may write:

$$H_{TC}^2 [2J_1'(2x_1/D)]^2 = H_{TC}^2 \left[\frac{2J_1(2x_2/D)}{x_2/D} \right]^2 \\ 35 = \frac{1}{2} H_{TR}^2 \sin^2 \pi \frac{x_2 + x_0}{a} = \frac{1}{2} H_{LR}^2 \cos^2 \pi \frac{x_1 + x_0}{a} \quad (2)$$

40 the coefficient $\frac{1}{2}$ in the two last equations being due to the fact that, in the rectangular guide, the variation of reactive energy in the vicinity of the slots is produced by the two waves applied to the ends of said guide.

45 It may be noticed that, whereas the three first expressions are quite equal with each other, it is not exactly true for the fourth. In fact in the three first expressions, the magnetic field which is concerned is the transverse one and the scattering by the slots of the pattern of said field normally produces a longitudinal displacement of the nodes of the standing waves in the rectangular guide. In the case of the symmetrical standing waves in the rectangular guide, it is the longitudinal component of the magnetic field which is concerned and has its pattern scattered by the slots. To the scattering of said field there would rather correspond a variation of the width of the rectangular guide than a longitudinal displacement of the nodes of the standing waves. Nevertheless, the fourth expression will be retained, but, as it is only roughly equal to the three other, the coupling system cannot suitably operate without supplementary means which will be disclosed hereinafter.

50 From Equations 2, one may derive:

$$65 \quad J_1'(2x_1/D) = \frac{J_1(x_2/D)}{x_2/D} \\ 70 \quad H_{LR} = \frac{\sin \pi \frac{x_2 + x_0}{a}}{a} = \frac{\lambda/2a}{\sqrt{1 - (\lambda/2a)^2}} \quad (3) \\ H_{TR} = \frac{\sin^2 \pi \frac{x_2 + x_0}{a}}{a} = \frac{b}{a} \frac{(\lambda/2a)^2 \sqrt{1 - (\lambda/2a)^2}}{1.94(\lambda/1.706D)^2 \sqrt{1 - (\lambda/1.706D)^2}}$$

in which λ is the wave length in free space of the wave which travels in the guides.

The first of the conditions which may be applied to the six quantities x_0 , x_1 , x_2 , a , b , D , which favours the construction and the operation of the coupler, is to make the cut-off wavelength λ_{CR} for the wave TE_{10} in the rectangular guide nearly that of the cut-off wavelength λ_{CC} for the wave TE_{11} in the circular guide, which is expressed by

$$2a = 1.706D \quad (4)$$

It is shown by the third Equation 3 that, when condition (4) is satisfied, the ratio b/a for a correct operation of the coupler is independent of the frequency.

As second and third conditions, there may be taken under a first hypothesis

$$x_1 = x_2 = 0 \quad (5)$$

that is to say, there may be imposed on the rectangular slots the condition of being concentric and, consequently, of forming a cross. There is then obtained

$$\begin{aligned} \tan \frac{\pi x_0}{a} &= \frac{\lambda/2a}{\sqrt{1 - (\lambda/2a)^2}} = \frac{\lambda}{2a} \\ \frac{b}{a} &= \frac{1}{1.94} \left(\frac{\lambda}{2a} \right)^2 \end{aligned} \quad (6)$$

The system of slots thus determined is that of a coupler of the prior art. As will be seen hereinafter in an example, the second Formula 6 gives, for the ratio b/a , lower values than those allowed in the standard rectangular guides and it is necessary to diminish b by transition 24 and 35 (Fig. 1) at the place of the slots; this constitutes a troublesome structural condition.

Under a second hypothesis, there may be imposed, as the second condition,

$$x_0 = \frac{a}{2} \quad (7)$$

that is to say, this second condition may be imposed for the axes of the rectangular and circular guides to meet each other. (This is the case which is effectively represented in Fig. 3, in which the axis Oy is midway between the sides 25 and 26, that is to say it coincides with the axis 20.)

The following results are then found as a function of the ratio

$$\begin{aligned} \frac{x_2}{a} &= \frac{1}{1.94} \left[\frac{\cos \frac{\pi x_2}{a}}{2J_1' \left(\frac{\pi x_2}{a} \right)} \right]^2 \\ \frac{\lambda}{2a} &= \frac{\cos \frac{\pi x_2}{a}}{\sqrt{\cos^2 \frac{\pi x_2}{a} + \sin^2 1.76 \frac{\pi x_2}{a}}} \end{aligned} \quad (8)$$

Formulae 8 enable x_1 , x_2 and b to be determined for a given value of the ratio

$$\frac{x_2}{a}$$

Let us suppose that it is desired to construct a directional coupler which allows a frequency band to pass which comprises between (3750-10) mc./s. and (3750+10) mc./s. corresponding to a mean wavelength in the unbounded space which is equal to $\lambda = 80.6$ mms. For this wavelength, there is chosen, as usual, a rectangular guide having a large side a such that

$$a = \frac{\lambda}{\sqrt{2}} = 57 \text{ mms.}$$

The dimensions of the coupling system are then the following under the first hypothesis:

$$\begin{aligned} D &= 66.8 \text{ mms.} \\ x_0 &= 14.25 \text{ mms.} \\ b &= 14.7 \text{ mms.} \end{aligned}$$

Under the second hypothesis, which is that of the present invention, the last of the Formulae 8 is, when

$$a = \frac{\lambda}{\sqrt{2}}$$

reduced to

$$15 \quad \cos \frac{\pi x_2}{a} = \sin \left(1.76 \frac{\pi x_2}{a} \right)$$

which gives

$$20 \quad \frac{x_2}{a} = \frac{1}{5.52}$$

The coupling system then has the following dimensions:

$$\begin{aligned} D &= 66.8 \text{ mms.} \\ x_1 &= 18.2 \text{ mms.} \\ x_2 &= 10.3 \text{ mms.} \\ b &= 26.6 \text{ mms.} \end{aligned}$$

It is observed that, under the first hypothesis

$$30 \quad \frac{b}{a} = 0.25$$

whilst, under the second hypothesis,

$$35 \quad \frac{b}{a} = 0.47$$

which value is acceptable because, in the standard guides, the ratio b/a is generally equal to about 0.44.

40 For theoretical reasons, above summarily explained, and in order to increase the transmission band of the directional couplers, it is necessary to arrange thin metallic plates parallel to the large sides of the rectangular guides and facing the portion of wall comprised between the 45 edge of the large side and the longitudinal slots. The positioning of these plates 24 is determined by trial and error. In the case of the foregoing example in which $b = 26.6$ mms., the plates are placed 3 mms. below the slots 22, i.e. at about an eighth of the height b , and they 50 extend inward as far as the axis of the slot 22, that is to say that they have a width which is very nearly equal to

$$\frac{a}{2} - x_1$$

55 Fig. 4 represents a directional channel-separation filter according to the invention.

The energy arrives from an aerial (not shown) through the main guide 32 which is terminated by a 60 dissipative load element in the form of, for example, an absorbent plate 33. This energy is constituted by a wide-band wave comprising two partial bands or channels.

Two circular cavity resonators 29 and 29' are coupled to the said main guide 32 by systems of slots 22-23 and 65 22'-23' of the type shown in Fig. 3. The circular resonators 29 and 29' are coupled to rectangular guides 27 and 27' by systems of slots which are identical with the foregoing. The guides 27 and 27' are terminated, at one of their mouths, by absorbent plates 28 and 28'. 70 The energy corresponding to the first channel is obtained at the mouth 30 of the guide 27 and the energy corresponding to the second channel is obtained at the mouth 30' of the guide 27'. Screws 31 and 31', four in number, in a diametral plane of the circular cavity resonators 75 29 and 29' provide tuning means for tuning the same,

to the central frequencies of the first and second channels respectively.

What I claim is:

1. A directional channel-separation filter adapted to separate a plurality of frequency channels contained in a large over-all bandwidth electromagnetic energy comprising a common rectangular main waveguide adapted to convey in the TE_{10} mode said electromagnetic energy, a plurality, equal to the plurality of frequency channels, of circular cavity resonators respectively tuned onto the mean frequencies of the frequency channels and adapted to support in the TE_{11} mode the electromagnetic energy of the corresponding channels, coupled to said rectangular main waveguide along the large side thereof and having axes meeting with the longitudinal axis of the rectangular main waveguide, a first equal plurality of slot-and-plate coupling systems coupling said rectangular main waveguide to said circular cavity resonators, an equal plurality of channel rectangular waveguides having the same cross-section than the rectangular main waveguide, respectively coupled along their large sides to said circular cavity resonators and having longitudinal axes respectively meeting with the circular cavity resonator axes, a second equal plurality of slot-and-plate coupling systems coupling said channel rectangular waveguides to said circular cavity resonators, each slot-and-plate coupling system of the first and second pluralities comprising a first slot longitudinal with respect to the rectangular waveguide to which it pertains, on one side of the longitudinal axis of said rectangular waveguide and spaced apart from said rectangular waveguide axis by a distance x_1 , and orthoradial with respect to the circular cavity resonator to which it pertains, a second slot transverse with respect to the rectangular waveguide to which it pertains, on the other side of the longitudinal axis of said rectangular waveguide and having a center spaced apart from said rectangular waveguide axis by a distance x_2 , and radial with respect to the circular cavity resonator to which it pertains, the centers of said slots being in a plane normal to the axis of the rectangular waveguide and diametrical with respect to the circular cavity resonator and the quantities x_1 and x_2 being related by the relationship $x_1 = 1.76x_2$, and a metallic plate located inside the rectangular waveguide and beneath the first slot only at a distance from said slot substantially equal to the eighth of the small side of the rectangular waveguide, an absorbent load at one end of the rectangular main guide and absorbent loads at one of the ends of the channel rectangular waveguides.

2. A directional channel-separation filter adapted to separate a plurality of frequency channels contained in a large over-all bandwidth electromagnetic energy comprising a common rectangular main waveguide adapted to convey in the TE_{10} mode said electromagnetic energy, a plurality, equal to the plurality of frequency channels, of circular cavity resonators respectively tuned onto the mean frequencies of the frequency channels and adapted to support in the TE_{11} mode the electromagnetic energy of the corresponding channels, coupled to said rectangular main waveguide along the large side thereof and having axes meeting with the longitudinal axis of the rectangular main waveguide, a first equal plurality of slot-and-plate coupling systems coupling said rectangular main waveguide to said circular cavity resonators, an equal plurality of channel rectangular waveguides having the same cross-section than the rectangular main waveguide, respectively coupled along their large sides to said circular cavity resonators and having longitudinal axes respectively meeting with the circular cavity resonator axes, a second equal plurality of slot-and-plate coupling systems coupling said channel rectangular waveguides to said circular cavity resonators, each slot-and-plate coupling system of the first and second pluralities comprising a first slot longitudinal with respect to the rectangular waveguide to which it pertains, on one side of

5 the longitudinal axis of said rectangular waveguide and spaced apart from said rectangular waveguide axis by a distance x_1 , and orthoradial with respect to the circular cavity resonator to which it pertains, a second slot transverse with respect to the rectangular waveguide to which it pertains, on the other side of the longitudinal axis of said rectangular waveguide and having a center spaced apart from said rectangular waveguide axis by a distance x_2 , and radial with respect to the circular cavity resonator to which it pertains the centers of said slots being in a plane normal to the axis of the rectangular waveguide and diametrical with respect to the circular cavity resonator and the quantities x_1 and x_2 being related by the relationships:

15

$$x_1 = 1.76x_2$$

20

$$\frac{\lambda}{2a} = \frac{\cos \frac{\pi x_2}{a}}{\sqrt{\cos^2 \frac{\pi x_2}{a} + \sin^2 \frac{1.76\pi x_2}{a}}}$$

25 λ being the mid-wavelength of the over-all bandwidth and a the great side dimensions of the rectangular guide, and a metallic plate located inside the rectangular waveguide and beneath the first slot only at a distance from said slot substantially equal to the eighth of the small side of the rectangular waveguide, an absorbent load at 30 one end of the rectangular main guide and absorbent loads at one of the ends of the channel rectangular waveguides.

3. A directional channel separation filter adapted to separate a plurality of frequency channels contained in a 35 large over-all bandwidth electromagnetic energy comprising a common rectangular main waveguide, having a large side dimension equal to a , adapted to convey in the TE_{10} mode said electromagnetic energy, a plurality, equal to the plurality of frequency channels, of circular cavity 40 resonators all having a diameter equal to $1.172 a$, respectively tuned onto the mean frequencies of the frequency channels and adapted to support in the TE_{11} mode the electromagnetic energy of the corresponding channel, coupled to said rectangular main waveguide along the large 45 side thereof and having axes meeting with the longitudinal axis of the rectangular main waveguide, a first equal plurality of slot-and-plate coupling systems coupling said rectangular main waveguide to said circular cavity resonators, an equal plurality of channel rectangular waveguides having the same cross-section than the rectangular main waveguide, respectively coupled along their large sides to said circular cavity resonators and having longitudinal axes respectively meeting with the circular cavity resonator axes, a second equal plurality of slot-and-plate 50 coupling systems coupling said channel rectangular waveguides to said circular cavity resonators, each slot-and-plate coupling system of the first and second pluralities comprising a first slot longitudinal with respect to the rectangular waveguide to which it pertains, on one side of the longitudinal axis of said rectangular waveguide and spaced apart from said rectangular waveguide axis by a distance x_1 , and orthoradial with respect to the circular cavity resonator to which it pertains, a second slot transverse with respect to the rectangular waveguide to which it pertains, on the other side of the longitudinal axis of said rectangular waveguide and having a center spaced apart from said rectangular waveguide axis by a distance x_2 , and radial with respect to the circular cavity resonator to which it pertains, the centers of said slots being 55 in a plane normal to the axis of the rectangular waveguide and diametrical with respect to the circular cavity resonator and the quantities x_1 and x_2 being related by the relationship $x_1 = 1.76x_2$, and a metallic plate located inside the rectangular waveguide and beneath the first slot only at a distance from said slot substantially equal to

75

the eighth of the small side of the rectangular waveguide, an absorbent lead at one end of the rectangular main waveguide and absorbent loads at one of the ends of the channel rectangular waveguides.
